CLAIM

The ornamental design(s) for a hair brush, as shown and described.

DESCRIPTION

FIG. 1 is a first perspective view of the hair brush;

FIG. 2 is a second perspective view of the hair brush;

FIG. 3 is a top plan view of the hair brush;

FIG. 4 is a bottom plan view of the hair brush;

FIG. 5 is a right side elevation view of the hair brush;

FIG. 6 is a left side elevation view of the hair brush;

FIG. 7 is a rear elevation view of the hair brush; and,

FIG. 8 is a front elevation view of the hair brush.

Any portions of the figures shown in broken lines illustrate environmental structure and form no part of the claimed design.
